(57) **CLAIM**

The ornamental design for a cable hanger, as shown and described.

DESCRIPTION

FIG. 1 is a perspective view from a first side of the new design for a cable hanger in accordance with the present invention;

FIG. 2 is a perspective view from a second side of the cable hanger shown in FIG. 1;

FIG. 3 is an end elevation view from a first end of the cable hanger shown in FIG. 1;

FIG. 4 is an end elevation view from a second end of the cable hanger shown in FIG. 1;

FIG. 5 is a side elevation view of the first side of the cable hanger shown in FIG. 1;

FIG. 6 is a side elevation view of the second side of the cable hanger shown in FIG. 1;

FIG. 7 is a top plan view of the cable hanger shown in FIG. 1;

FIG. 8 is a bottom plan view of the cable hanger shown in FIG. 1;

FIG. 9 is a perspective view from a first side of another embodiment of the new design for a cable hanger in accordance with the present invention;

FIG. 10 is a perspective view from a second side of the cable hanger shown in FIG. 9;

FIG. 11 is an end elevation view from a first end of the cable hanger shown in FIG. 9;

FIG. 12 is an end elevation view from a second end of the cable hanger shown in FIG. 9;

FIG. 13 is a side elevation view of the first side of the cable hanger shown in FIG. 9;

FIG. 14 is a side elevation view of the second side of the cable hanger shown in FIG. 9;

FIG. 15 is a top plan view of the cable hanger shown in FIG. 9; and,

FIG. 16 is a bottom plan view of the cable hanger shown in FIG. 9.

(Continued)

The broken lines within the various embodiments of the claimed design and the spaces therein are for environmental purposes only and form no part of the claimed design.
